TICKET AND TICKET HOLDER

Murdock Macdonald, East Cleveland, Ohio

Application August 16, 1932, Serial No. 629,011

5 Claims. (Cl. 206—40.6)

The present invention relating as indicated to a ticket and ticket box holder, is more particularly directed to an improved ticket and stub therefor adapted to prevent repunching of the stub by the conductor in such a way as to permit of fraud in the sale of tickets, and to a box or ticket holder adapted to receive, contain, punch, and deliver tickets of the character referred to. To the accomplishment of the foregoing and related ends, said invention, then, consists of the means hereinafter fully described and particularly pointed out in the claims.

The annexed drawing and the following description set forth in detail certain structure embodying the invention, such disclosed means constituting, however, but one of various structural forms in which the principle of the invention may be used.

In said annexed drawing:

Fig. 1 is a view in perspective of my improved ticket box holder with tickets therein; Fig. 2 is a plan view of the same; Fig. 3 is a plan view of a duplicate ticket punched and separated and in extended condition, showing the relation between the punched ticket and the stub thereof; Fig. 4 is a section on the line 4—4, Fig. 2; Fig. 5 is a similar section but showing the operating bar of the ticket holder displaced to pick up the stub of the separated ticket; Fig. 6 is a similar view showing the displacement of the stub upon the return to normal position of the operating bar; and Fig. 7 is a section on the line 7—7, Fig. 2.

A common type of ticket employed on many interurban electric roads, bus lines and steam railways consists of rectangular printed forms carrying a list of stations along one edge and duplicate columns elsewhere on the form in which dollars and cents are indicated and which are adapted to be punched or notched by tearing the ticket against an operating bar provided with movable notching members or by actually removing the ticket from the pad or box and punching in these duplicate columns the amount of the fare collected.

All such tickets lend themselves to misuse by the conductor if so minded since he can punch or notch the portion of the ticket given to the passenger and then punch in a different manner the stub which will show one rate to the company's auditors and another to the passenger allowing the conductor to pocket the difference in money. To avoid this it has been heretofore necessary to employ extremely complicated tickets or sealed ticket boxes none of

which have been commercially practical. I have devised a simple duplicate ticket and a simple open box-like holder therefor which permit of rapid and convenient marking or notching of the ticket to indicate the fare paid, the rapid severing of the passenger's portion of the ticket from the balance of the form and the retention and subsequent discharge of the stub which is necessarily notched to exactly correspond with the portion of the ticket given to the passenger.

In Fig. 1 I have shown in perspective my improved holder consisting of the box-like casing 1 provided with flange portions 2, 3 and 4 and adapted to receive a series of ticket forms 5. An operating bar 6 provided with a straight edge 7 against which the tickets are designed to be torn off is mounted in the holder 1, the bar 6 having upturned ends 8 in which is mounted a rod 9 which extends beyond the casing proper and is engaged and retained by means of a wire 10 running to the end 11 of the rod, then around the right side of the casing where it engages in the flange portion 4 of the casing, as indicated, and then to a lug 12 on the other end of the rod 11. A compression spring 13 is mounted around the last-mentioned part of the wire 10 and serves to maintain the upper end of the operating bar 6 in the position shown in Fig. 1. The bar 6 is also provided with a flange 14, the purpose of which will presently be described.

Slidably mounted on the rod 9 are a series of notching elements 15, 16, 17 and 18 which, in the normal position of the bar, overlie the column of figures shown on that portion of the ticket which is to be delivered to the passenger. It will be understood that the ticket may take various forms and bear various indicia depending on its uses, but in the form indicated it consists of re-doubled duplicate portions 20 and 21, the portion 20 being folded under the portion 21 with its indicia in registration with those of the upper part 21 so that any mark, punch or notch formed on one-half the ticket is similarly reproduced on the other half.

At the right of the ticket is a series of stations arranged successively for the route on which the ticket is to be used while at the left of the ticket are the duplicate columns of figures 25 and 26 separated by a broad, printed space 27 in which the notching is to be done. In use, the conductor first punches, if desired, the stations between which the ticket is used by punching in the proper portions of the columns

on the right of the ticket, after which he moves the upper notching element 18 to indicate whether the ticket is a half fare or adult ticket and then moves the other notching members 15, 5 16 and 17 to show the proper amount of money received for the ticket in cents, dimes and dollars. He then lifts the upper right hand corner of the ticket and tears it against the operating bar, the notching members producing notches 10 31 in the left hand margin of the ticket and the duplicate thereof, which overlies the ticket, showing on the top of the pad in the manner indicated in Fig. 3. At the same time projections 32 corresponding to the notches just 15 referred to are formed in the blackened or printed margin portions of the stub, as indicated in Fig. 3. The conductor then tears the duplicate from the ticket proper, retaining the original for the company and handing the passenger the duplicate, both of which will bear precisely the same punching marks and indicate the payment of exactly the same amount of fare.

25 The conductor will then press the flanged portion 14 of the holding bar to the right against the action of the spring 13 a sufficient distance to bring a plate 33 mounted on the lower side of the bar 6 to the position shown in Fig. 5 and at the right edge of the stub of the ticket. 30 By releasing the bar the spring is enabled to return it to its normal position, the plate 33 forcing the upper left hand corner of the stub out of the box when it may be grasped by the conductor and withdrawn, and retained for 35 turning into the company together with the company's portion of the ticket.

40 A pad of tickets may be inserted in the holder by snapping the bent portion 40 of the wire 10 out of the rounded flange 41 on the flange 4 on the holder, when the bar 6, rod 9, and associated parts may be swung in a clockwise direction as the holder is viewed in Fig. 1, to lift the bar away from the holder and permit the introduction of a fresh pad of tickets, after which 45 the bar may be swung back into the position shown and the portion 40 of the retaining rod snapped under the curved flange 41 again.

50 Auditing of the tickets and stubs then becomes a simple matter since both the company's portion of the ticket and the company's stub must show exactly the same fare while the duplicate of the stub will necessarily show the exact fare punched on the passenger's ticket. In this way it becomes impossible for the conductor to 55 punch the company's and the passenger's copy of the ticket proper differently since both must be punched simultaneously and since the two stubs will reflect accurately the amounts of fare punched or notched on the tickets proper.

60 By the use of a ticket of this type provided with an intermediate notchable portion between duplicate columns of figures indicating the fare and by the use of my improved holder which makes it necessary to notch simultaneously the company's ticket, the passenger's ticket and the 65 stubs, it becomes practically impossible for the conductor to register different fares on the tickets and on the stubs without detection. The entire device is extremely simple and inexpensive and is easy to operate, while the ticket forms 70 are also simple.

Other modes of applying the principle of my invention may be employed instead of the one

explained, change being made as regards the mechanism herein disclosed, provided the means stated by any of the following claims or the equivalent of such stated means be employed.

I therefore particularly point out and distinctly 5 claim as my invention:

1. A ticket holder consisting of a holder proper adapted to receive a plurality of duplicate tickets, a severing bar mounted adjacent one side of said holder on top of said tickets and extending longitudinally of the holder, said bar being displaceable laterally of the holder, notching means movably carried on said bar, and means mounted on the lower surface of said bar for discharging the stub of a severed ticket upon lateral displacement of said bar across said holder. 10 15

2. A ticket holder consisting of a holder proper adapted to receive a plurality of duplicate tickets, a severing bar mounted in said holder on top of said tickets and extending longitudinally of the holder, said bar being displaceable laterally of the holder and having severing and non-severing edges, notching means movably carried on said bar, and means for discharging the stub of a severed ticket upon lateral displacement of said bar across said holder, said means comprising a member mounted on the lower surface of said bar adjacent one end thereof, said member having a stub-displacing 20 25 edge intermediate the severing and non-severing edges of said severing bar.

3. In a ticket holder, a holder adapted to receive a plurality of duplicate tickets, a severing bar mounted in said holder on top of said tickets and extending longitudinally of the holder, said bar being displaceable laterally of the holder and having an upstanding flange adjacent one end thereof providing means for manually moving the bar, and means for discharging the stub of a severed ticket upon lateral displacement of said bar across said holder, said means comprising a plate-like member mounted on the lower surface of said bar and having a stub displacing edge intermediate the severing edge of said 35 40 45 bar and said flange.

4. A ticket holder consisting of a holder proper adapted to receive a plurality of duplicate tickets, a severing bar in said holder overlying the tickets therein and manually movable from a normal position parallel with one side of the holder to non-parallel position with respect to said side, and a compression spring for automatically restoring said bar to its normal position upon release of the bar after movement 50 55 thereof.

5. A ticket holder consisting of a holder proper adapted to receive a plurality of duplicate tickets, a severing bar in said holder overlying the tickets therein and provided with stub-ejecting means, a wire member retaining said bar in engagement with said tickets, said wire providing a pivotal mounting for one end of said bar, said bar being manually movable about said pivot from a normal position in which its severing edge is parallel with one side of the holder to a position in which said edge is non-parallel with said side of the holder, and spring means for automatically restoring the bar to its normal position upon release of the bar after 60 65 70 movement thereof.

MURDOCK MACDONALD.
